US0D1008260S

(12) **United States Design Patent** (10) **Patent No.:** **US D1,008,260 S**
(45) **Date of Patent:** **** Dec. 19, 2023**

(54) **DISPLAY STAND WITH WEARABLE DEVICE**

(71) Applicant: **Apple Inc.**, Cupertino, CA (US)

(72) Inventors: **Jody Akana**, Los Altos Hills, CA (US); **Molly Anderson**, San Francisco, CA (US); **Bartley K. Andre**, Palo Alto, CA (US); **Shota Aoyagi**, San Francisco, CA (US); **Anthony Michael Ashcroft**, San Francisco, CA (US); **Marine C. Bataille**, San Francisco, CA (US); **Jeremy Bataillou**, San Francisco, CA (US); **Daniele De Iuliis**, San Francisco, CA (US); **Markus Diebel**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Julian Jaede**, San Francisco, CA (US); **Duncan Robert Kerr**, San Francisco, CA (US); **Peter Russell-Clarke**, San Francisco, CA (US); **Benjamin Andrew Shaffer**, San Jose, CA (US); **Mikael Silvanto**, San Francisco, CA (US); **Christopher J. Stringer**, Woodside, CA (US); **Sung-Ho Tan**, Vienna (AT); **Clement Tissandier**, San Francisco, CA (US); **Eugene Antony Whang**, San Francisco, CA (US); **Rico Zörkendörfer**, San Francisco, CA (US)

(73) Assignee: **Apple Inc.**, Cupertino, CA (US)

(**) Term: **15 Years**

(21) Appl. No.: **29/863,097**

(22) Filed: **Dec. 15, 2022**

Related U.S. Application Data

(63) Continuation of application No. 29/680,991, filed on Feb. 21, 2019, now Pat. No. Des. 973,404, which is (Continued)

(57) **CLAIM**

The ornamental design for a display stand with wearable device, as shown and described.

DESCRIPTION

FIG. 1 is a top front perspective view of a display stand with wearable device showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the figures show portions of the display stand with wearable device that form no part of the claimed design.

1 Claim, 5 Drawing Sheets

Related U.S. Application Data

a continuation of application No. 29/635,673, filed on Feb. 1, 2018, now Pat. No. Des. 841,373, which is a continuation of application No. 29/571,404, filed on Jul. 18, 2016, now Pat. No. Des. 810,478.
